(57) **CLAIM**

We claim the ornamental design for a shade assembly, as shown and described.

DESCRIPTION

FIG. 1 is a top perspective view of a shade assembly of the present invention.

FIG. 2 is an enlarged top perspective view of the shade assembly of FIG. 1.

FIG. 3 is a front elevation view of the shade assembly of FIG. 1.

FIG. 4 is a left side elevation view of the shade assembly of FIG. 1.

FIG. 5 is a top plan view of the shade assembly of FIG. 1.

FIG. 6 is a rear elevation view of the shade assembly of FIG. 1.

FIG. 7 is a right side elevation view of the shade assembly of FIG. 1.

FIG. 8 is a bottom plan view of the shade assembly of FIG. 1.

FIG. 9 is a top perspective view of another version of a shade assembly of the present invention.

FIG. 10 is an enlarged top perspective view of the shade system of FIG. 9.

FIG. 11 is a front elevation view of the shade assembly of FIG. 9.

FIG. 12 is a left side elevation view of the shade assembly of FIG. 9.

FIG. 13 is a top plan view of the shade assembly of FIG. 9.

FIG. 14 is a rear elevation view of the shade assembly of FIG. 9.

FIG. 15 is a right side elevation view of the shade assembly of FIG. 9; and,

FIG. 16 is a bottom plan view of the shade assembly of FIG. 9.

The broken lines in the drawing depict environmental subject matter and form no part of the claimed design.
